UNITED STATES PATENT OFFICE.

MERRILL A. FURBUSH, OF PHILADELPHIA, PENNSYLVANIA, ASSIGNOR TO HIMSELF AND CHARLES A. FURBUSH, OF SAME PLACE.

CREEL-FRAME FOR CARDING-MACHINES.

SPECIFICATION forming part of Letters Patent No. 254,301, dated February 28, 1882.

Application filed November 23, 1881. (No model.)

To all whom it may concern:

Be it known that I, MERRILL A. FURBUSH, a citizen of the United States, residing in Philadelphia, Pennsylvania, have invented certain 5 Improvements in Creel-Frames for Carding-Machines, of which the following is a specification.

The object of my invention is to permit the feeding into a second breaker or condenser carding-machine, without inconvenience, of a much greater number of ends or rovings than is now possible; and this object I attain by so constructing the frame carrying the feeding creels or spools that it will have a large capacity without exceeding proper limits as regards either 15 size or weight, and without interfering with the proper piecing of the rovings as the spools become successively unwound and have to be replaced.

20 In the accompanying drawings, Figure 1, Sheet 1, is an end view, partly in section, of my improved creel-frame, showing the relation of the same to the carding-machine; Fig. 2, Sheet 2, a front view of the frame; and Fig. 3, 25 Sheet 1, a diagram illustrating the main feature of my invention.

The frame comprises opposite end plates or standards, A A, suitably connected and braced by transverse bars *a* at top and bottom. This 30 frame carries a number of pairs of horizontal spool-supporting rolls, B D, arranged vertically in two sets or series, each series comprising in the present instance five pairs of rollers, and the rollers B, forming one series, being arranged 35 directly in advance of the rollers D, comprising the other series.

What are termed "spools" are simply cores on which the sliver or roving from the breaker-card is wound, the roving resting directly upon 40 one of the pairs of rolls B D, so that as the latter are rotated the roving will be unwound and fed forward as fast as it is drawn in by the feed-rolls *x x* of the carding-machine X. The rolls are adapted to bearings in brackets *b* on 45 the end frames, A, and are of such a length that a number of spools can be arranged side by side on each pair of rolls, vertical rods *c* being arranged at suitable intervals between the rolls, so as to prevent the contact of adjacent spools. 50 The rovings are drawn from the under sides

of the spools, as shown in Fig. 3, the rovings from the rear spools being passed beneath the front spools and over the supporting-rolls of the same, and thence to the feed-rolls of the carding-machine with the rovings from said 55 front spools.

A creel-frame constructed in this manner is very compact, and is adapted for the reception of a much larger number of spools than creel-frames of like size as now constructed, so that I 60 am, without sacrifice of space, enabled to feed to the carding-machine two or three times as many ends or rovings as is now considered practicable, thus gaining in the carding-machine the valuable results of doubling and producing 65 woolen yarns of a more uniform character than is possible with the methods at present in use. The arrangement of the spools in the frame is such that piecing of the ends can be effected entirely from the back or unobstructed part 70 of the frame. Thus when one of the front spools is nearly unwound the attendant simply frees the end of the roving, removes the core of the spool, and allows the free end of the roving to fall between the rolls B and D, the 75 rear spool being then rolled forward from the rolls D to the rolls B and the end of the first roving carried to the back of the frame and pieced to the roving of a fresh spool, which is deposited on the rolls D. This facility for piec- 80 ing from the back of the frame is an important feature, as access to the front of the frame is impracticable, owing to the delivery of the rovings at this part of the frame. The empty core is removed over the top of the rear spool 85 by the attendant standing at the rear of the frame; or, if the rear spool is so full of sliver that there is not room enough between it and the rolls above to permit such removal, said spool may be removed from the rolls D and 90 held in one hand while the empty core is removed from the front rolls with the other hand.

Various means of driving the rolls B and D will readily suggest themselves to those familiar with this class of machinery. The means 95 which I have found to answer well in practice and which I prefer to adopt are shown in Figs. 1 and 2, and comprise an endless chain, E, adapted to wheels F, carried by short counter-shafts G, turning in bearings on the brackets *b* 100

at one end of the frame, these shafts being furnished with worms *d*, which engage with worm-wheels *e* on the spindles of the rolls *B* and *D*. The chain is kept tight by means of an adjustable friction-roll, *J*, and is driven by a wheel, *K*, on a shaft, *g*, the latter forming a continuation of one of the rotating shafts of the carding-machine, or being driven in any other manner which seems to be appropriate.

10 I have shown in the drawings a creel-frame with but two sets or series of spool-supporting rolls; but in practice it may be found expedient to construct the frame with three or more sets of such rolls.

15 I claim as my invention—

1. The combination, in a creel-frame, of a supporting-structure and driving mechanism with two sets of spool-supports, each set comprising a number of pairs of horizontal rolls, arranged one pair above another, and the rolls of one set being in the rear of the rolls of the other set, as specified.

2. The combination, in a creel-frame, of a supporting-structure and driving mechanism with two sets of spool-supports, each set comprising a number of pairs of horizontal rolls, arranged one pair above another, and the rolls of one set being in the rear of the rolls of the other set, and so close thereto that a spool can be rolled directly from one set to the other, as specified.

3. The combination of the supporting-structure, the two sets of spool-supporting rolls *B* *D*, with worm-wheels *e*, the endless chain *E*, the shafts *G*, with wheels *F* and worms *d*, and the driving-shaft *g*, with wheel *K*, as set forth.

In testimony whereof I have signed my name to this specification in the presence of two subscribing witnesses.

M. A. FURBUSH.
